UNITED STATES PATENT OFFICE.

FREDERICK A. PRESTON, OF HIGHLAND PARK, ILLINOIS, ASSIGNOR TO THE P. & M. CO., OF CHICAGO, ILLINOIS, A CORPORATION OF ILLINOIS.

ANTICREEPER.

1,163,172.

Specification of Letters Patent. Patented Dec. 7, 1915.

Application filed June 1, 1915. Serial No. 31,416.

To all whom it may concern:

Be it known that I, FREDERICK A. PRESTON, a citizen of the United States, residing at Highland Park, in the county of Lake and State of Illinois, have invented new and useful Improvements in Anticreepers, of which the following is a full, clear, concise, and exact description, reference being had to the accompanying drawing, forming a part of this specification.

10 My invention relates to means for preventing the creeping or longitudinal movement of railroad rails, such devices being called anti-creepers or rail anchors.

15 The general object of my invention is to provide an improved one-piece anti-creep.

Another object is to provide an anti-creep which is secured to one side only of the rail base without requiring auxiliary 20 fastening devices.

A further object is to provide a one-piece anti-creep which is under stress after being applied to the rail base whereby it maintains its grip thereon under varying conditions of expansion, contraction, vibration 25 and rearward movement of the rail.

An additional object is to provide a very light, simple, inexpensive and effective anti-creep.

30 In the accompanying drawings, I have illustrated several embodiments of the invention. Various changes are, of course, contemplated in the forms shown, and various other forms may be devised, all of 35 which fall within the scope of the invention.

Figure 1 is a side elevation of a rail with the anti-creep applied thereto. Fig. 2 is a rear elevation of said anti-creep, the rail being shown in section. Fig. 3 is a perspective view of said anti-creep. Fig. 4 is a side elevation of a modified form of anti-creep. Fig. 5 is a perspective view of a further modified form. Fig. 6 is a perspective view of an additional modified form. 45 Fig. 7 is a rear elevation partly in section of another modification.

The rail 1 is supported by the usual cross-tie 2. The rail anchor 3 is made preferably of tempered spring steel, the dimensions being 50 subject to considerable variation depending on conditions. In the forms shown in Figs. 1, 2 and 3, the spring steel is in the form of a flat plate or strip bent so as to form what may be termed a U shaped construction, one arm 4 of the U, however, being

much longer than the other arm 5. The longer arm is provided with an opening or jaw 6 of slightly less dimensions than the corresponding section of the rail base, whereby when the jaw is forced on to the rail base, it will be sprung somewhat, thereby exerting a powerful grip on the rail base flange. Since the rail anchor is applied to one flange only of the rail base and maintains its hold thereon by virtue of its frictional grip, being unassisted by auxiliary fastening devices or other means providing for a positive hold thereon, this feature of springing or distorting the rail anchor slightly to make it grip the rail base with an enormous pressure, is an important one.

In order to minimize the tendency of the anchor to move laterally away from the rail due to the resultant side thrust arising out of the inclined relation of the upper and lower walls of the jaw, I provide one of said walls, for example the upper wall, with a roughened surface to better resist said lateral tendency. The roughened surface may take the form of saw teeth 7 inclined backward so that as the anchor is driven on to the base flange, said teeth do not oppose said movement, but they do oppose any reverse movement, namely a movement which would move the anchor away from the rail base flange. After the anchor has been driven on to the rail base flange as far as possible, a firm hold thereon is inserted by striking the top of the anchor with a hammer or maul which tends to make the teeth bite into the top of the base flange of the rail. Such blow or blows do not necessarily result in indenting the rail to an objectionable degree, but merely insures the teeth against possible slipping.

The lower end of the arm 4 bears against the side of the cross-tie 2 thereby transmitting to said tie, the creeping thrust produced by the rail. The reaction of the tie against the lower part of the anti-creep 95 produces, of course, a tendency to tilt the anti-creep about a horizontal axis. This tilting is not objectionable, but on the contrary, would tend to increase the grip of the anti-creep on the rail base. In the form of 100 device under discussion, however, the tilting action is resisted by the shorter arm 5 which bears against the base of the rail and exerts an upward thrust thereon. Said arm 5 is 105 slightly longer than the corresponding and 110

substantially parallel portion of the arm 4 which terminates in the lower surface of the jaw, also bearing against the under side of the rail base. This slightly extra length 5 results in a tendency to tilt the anchor in a direction, the reverse of which it tends to be tilted by the creeping thrust of the rail. In driving the anchor on to the rail base, however, the arm 4 is forced to assume a position 10 substantially vertical. The arm 5 being too long to permit this arrangement under normal conditions, the anchor is forcibly distorted somewhat, the arm 5 being under considerable compression and exerting 15 a powerful upward thrust against the rail base, the reaction being in the form of a powerful downward thrust by the arm 4 increasing the bite of the teeth 7 against the top of the rail base. The anchor, in 20 final position, may be vertical or may be tilted slightly as shown in the drawings, depending on the length of the arm 5. The distortion of the anchor, in general, is responsible for still further increasing the 25 frictional engagement between the rail anchor as a whole and the rail base, whereby said rail anchor maintains its grip on said rail base independently of any reactions due to the creeping thrust. As a result, said 30 hold is effectively maintained even if the rail undergoes a rearward movement withdrawing the rail anchor from engagement with the tie. In other words, the rail anchor does not loosen its hold or fall off the rail 35 even when withdrawn from operative engagement with the tie, nor do relative differences in the expansion and contraction of the rail and of the rail anchor result in such loosening. Instead, the rail anchor adheres 40 to the rail, under all conditions, and when a forward movement thereof is subsequently produced by the rolling stock, said rail anchor reengages the tie and resists further creeping. The biting of the teeth into the 45 rail flange not only helps to hold the rail anchor against lateral movement, but also against movement along the rail; in other words, it assists in preventing the rail from slipping through the anchor.

50 In Fig. 4, I have illustrated a modified form of anti-creepers 8 which is substantially the equivalent of two anti-creepers such as shown in Figs. 1, 2 and 3, and formed integrally, resulting in a structure having substantially the form of a W in side elevation. This anti-creepers may be applied equally well to either side of the rail base, providing a structure which is longer in a direction 55 parallel to the length of the rail than the preceding construction. The tilting tendency is therefore resisted to a correspondingly greater extent. The pressure exerted by the two jaws against the top of the base flange is practically double the pressure 60 exerted by one jaw alone. Accordingly,

the frictional engagement with the rail base is correspondingly increased. Before the rail anchor is applied the two longer arms are substantially parallel, but when the rail anchor is in position, said arms incline 70 slightly toward each other as shown, in the drawing, for reasons which will be fully understood in view of the description of the preceding form of anchor.

The rail anchor 9 shown in Fig. 5 is substantially the same as the arm 4 of the forms previously described, the bent-up lower ends being omitted. Under these conditions, there is a tendency for the anti-creepers to tilt somewhat. However, the metal of which the rail anchor is composed, is of such thickness, and the rail anchor is sprung so firmly over the base flange, that whatever tilting takes place is inconsequential, and to whatever extent it does occur, it tends to increase 85 the grip of the anti-creepers on the rail base. This form of anti-creepers may be applied equally well to either side of the rail base and on the same side of the tie.

In Fig. 6 the rail anchor is substantially similar to that shown in Fig. 5, but is slightly modified by bending rearwardly the extremity 10, thereby providing a rearwardly extending reinforcing flange intended to bear upwardly against the bottom of the 95 rail, and further resists the tilting tendency.

Although as previously stated, all of the foregoing forms of rail anchor adhere to one side of the rail base without auxiliary fastening devices, nevertheless, means may be provided if desired, to positively lock the anchor on the rail. In Fig. 7 I have shown a further modified form of anchor 11 which is similar to that shown in Fig. 4 except that an arm 12 projects laterally beneath the rail base and has an upturned end 13 which engages the opposite side of said rail base. Said arm is integral with the rest of the anchor and joins it at the point where the two short arms unite and is formed by simply leaving a lateral extension at the middle of the plate which is stamped out in a die. Said arm being resilient, it may be sprung downwardly about as shown in dotted lines in said figure when the anchor is being applied, but it snaps upwardly to operative position as soon as the projection clears the edge of the rail base. The fastening arm 12 in the form illustrated in Fig. 7 or in some modified form, may be employed, of course, in connection with any one of the forms of anti-creepers illustrated in the remaining figures of the drawing.

Although I have described all of the forms of rail anchors as being made of a relatively thin plate of tempered steel, I do not limit myself to said material, or to a rail anchor of the general proportions implied by the term "plate," as certain of the advantageous features of the invention may 125

be obtained with other constructions. Furthermore, the teeth need not necessarily be on the upper side of the jaw. Various other changes may also be made without departing from the invention as defined in the appended claims.

Having thus described my invention what I claim as new and desire to secure by Letters Patent of the United States is:

- 10 1. An anti - creeper comprising a metal jaw, the opening of which is slightly less than the corresponding section of the rail base whereby said jaw is sprung when forced on to one side of said rail base and maintains its hold thereon to resist creeping without auxiliary fastening means.
- 15 2. An anti - creeper comprising a metal plate having an opening therein of slightly less dimensions than the corresponding section of one side of a rail base whereby said plate is sprung when forced on to said side and maintains its position thereon entirely by its frictional grip, said anti - creeper bearing directly against a cross tie to resist 25 creeping.
- 20 3. A rail anchor comprising a plate of tempered steel having a wedge shaped opening therein corresponding in outline to one side of a rail base, the walls of said opening being at right angles to the sides of said plate and the latter being arranged substantially at right angles to the length of the rail.
- 25 4. A rail anchor comprising a plate of tempered steel having a wedge shaped opening therein corresponding in outline to one

side of a rail base, the walls of said opening being at right angles to the sides of said plate, and an extension on said plate engaging the rail base to resist tilting. 40

5. A rail anchor comprising a steel plate having an opening therein forming a jaw arranged to receive the base flange with said plate transversely with respect to the length of the rail, one side of said jaw having teeth which are adapted to bite into the base flange of the rail to prevent lateral movement of said plate.

6. A rail anchor, comprising a U shaped metal plate, one arm being longer than the other and having an opening to receive the rail base.

7. A rail anchor, comprising a U shaped metal plate, having one arm longer than the other, the longer arm having an opening to receive the rail base, the lower surface of said opening being lower than the upper surface of the other arm.

8. A rail anchor, comprising a pair of jaws which grip the same side of the rail base, in combination with means between said jaws, bearing upwardly against the rail base to maintain said jaws under tension.

9. A rail anchor, comprising a vertical plate, having a notch therein which receives one side of the rail base, and having a rearwardly arranged extension which bears upwardly against the rail base to resist tilting.

In witness whereof, I have hereunto subscribed my name this 26th day of May, 1915.

FREDERICK A. PRESTON.
